DISPENSING CAP

Lloyd J. Schimke, Box 1272, Highway 2 E.,
Minot, N. Dak. 58701

Filed Oct. 12, 1972, Ser. No. 297,156

Term of patent 14 years

Int. Cl. D9—07

U.S. Cl. D9—278

FIG. 1

FIG. 4

FIG. 2

FIG. 5

FIG. 3

FIG. 6

FIG. 7

FIG. 10

FIG. 8

FIG. 11

FIG. 9

FIG. 12

FIG. 1 is a perspective view of a dispensing cap, showing my new design;

FIG. 2 is a top plan view;

FIG. 3 is a left side elevational view;

FIG. 4 is a front elevational view;

FIG. 5 is a bottom plan view;

FIG. 6 is a rear elevational view;

FIG. 7 is a perspective view of a modified form of my dispensing cap;

FIG. 8 is a top plan view thereof;

FIG. 9 is a left side elevational view;

FIG. 10 is a front elevational view;

FIG. 11 is a bottom plan view; and

FIG. 12 is a rear elevational view.

I claim:

The new and ornamental design for a dispensing cap, as shown and described.
